CLAIM

The ornamental design for a clamp, as shown and described.

DESCRIPTION

FIG. 1 is a front/side elevational perspective view of the clamp;

FIG. 2 is a first side view of the clamp;

FIG. 3 is a second side view of the clamp;

FIG. 4 is a rear view of the clamp;

FIG. 5 is a front view of the clamp;

FIG. 6 is a bottom view of the clamp; and,

FIG. 7 is a top view of the clamp.

The broken lines in the figures represent portions of the
clamp that form no part of the claim design.**1 Claim, 7 Drawing Sheets**(56)
